UNITED STATES PATENT OFFICE.

SAMUEL E. REUTTER, OF CLEARFIELD, PENNSYLVANIA.

LOCK.

1,164,016.

Specification of Letters Patent. Patented Dec. 14, 1915.

Application filed June 15, 1914. Serial No. 845,249.

To all whom it may concern:

Be it known that I, SAMUEL E. REUTTER, a citizen of the United States, residing at Clearfield, in the county of Clearfield and State of Pennsylvania, have invented a new and useful Improvement in Locks, of which the following is a specification.

This invention relates to a mortise door lock which has only one lock bolt and which can be either locked or unlocked from the inside of the door without the use of a key or set from the inside of the door, without the use of a key, so that the door can be opened from the outside by turning the outside knob and without the use of a key and set from the inside of the door without the use of a key, so that the door can be opened from the outside only with the use of a key. These objects are attained by the mechanism illustrated in the accompanying drawings, in which:

Figure 1 is a horizontal section taken through the lock on the line of the knob handles. Fig. 2 is a face view of the bolt, parts of the bolt casing and securing pins and the actuating shaft being in section, the bolt being in locking position. Fig. 3 is a similar view taken from the opposite side of Fig. 2 and showing the bolt in unlocking position. Fig. 4 is a rear view of the complete device shown in position. Fig. 5 is a section on the line 5—5 of Fig. 1.

In the drawings 1 represents a suitable bolt casing inserted into the door and contained within said casing is a bolt, 2, the outer end portion of which is beveled in the usual manner and within said casing said bolt is provided with a beveled shoulder 3 upon one side. The rear end of the bolt is of considerable width and is provided adjacent its opposite sides with grooved cam slots 4 and with a longitudinally extending slot 5, which is placed substantially upon the longitudinal center of the bolt. Through the slot 5 passes a suitable shaft 6, and said shaft is provided throughout the greater portion of its length with a longitudinally extending V-shaped slot 7. Keyed upon said shaft and also within the casing 1 is a transversely arranged yoke 8 which yoke carries adjacent its opposite ends rollers 9, which rollers rest within cam slots 4. It will be obvious that from this construction no matter in which direction the shaft 6 is rotated one of the rollers 9 will bear against the rear end of its cam slot 4, while the

other will travel idly in its slot, and the bolt will be retracted. A suitable spring 10 is also arranged within the casing and the free end portion of said spring bears upon the shoulder 3 of the bolt and returns the same to normal locking position. Upon the inside of the door the shaft 6 carries a sleeve 11, which sleeve extends into the shaft opening and at a point adjacent the casing 1 the sleeve is provided with a tongue 12, which engages the notch 7, the shaft being adapted to have a slidable movement in said sleeve, and projecting beyond the outer end of the sleeve. An inside knob 13 is fixed upon the sleeve 11 and an outside knob 14 is carried by a suitable sleeve 15. The inner end of the sleeve 15 is notched or slotted as shown at 16 and these slots are adapted to be engaged by a pin 17 when the shaft 6 is pushed inwardly.

A coil spring 18 arranged within the sleeve 15 bears at its outer end against the knob 14 and at its inner end against the shaft 6 and normally holds the pin 17 out of engagement with any of the slots 16. Consequently under normal conditions the knob 14 will turn loosely and without actuating the shaft 6 or retracting the bolt. The knob 14 however is provided with a suitable key-opening 19 and the inner end of the shaft 6 is provided with a slot 20, and a proper key may be passed through the opening 19 through the sleeve 15 and into engagement with the slot 20 thereby enabling the shaft 6 to be turned by said key. But I have also arranged for the locking of the shaft 6 to the outer knob 14 by means of the pin 17 so that when so locked the door may be opened from either side. This locking device consists of a small disk 21 secured to the inner end of the shaft, said disk being provided with a circumferential groove 22 adjacent the shaft. Upon the outer end of the shaft 6 which is upon the inner side of the door is rotatably mounted said disk 21 having a circumferential groove 22 and notched as shown at 22^a, said notch normally forming a continuation of the groove 7. The knob 13 has a tongue 12^a which also extends into the groove 7 and by pushing inwardly upon the disk 21 the shaft 6 will slide with respect to the knob and the tongue 12^a will rest in the groove 22. By then rotating the disk 21 the notch 22^a will be thrown out of alignment with the groove 7 and the shaft locked against outer movement with respect to the

knob 13. This movement also brings the pin 17 into engagement with one of the slots 16 of the sleeve 15, compressing the spring 18. The knob 14 is now locked to the shaft 5 and the door may be opened from either side.

It will be obvious from the above description that I have provided a lock and operating means therefor which fulfills all of the 10 objects previously specified.

What I claim is:—

1. In a device of the kind described a shaft having a groove, a yoke keyed upon said shaft, a bolt having cam slots therein, 15 rollers carried by the yoke and adapted to work in said slots and a spring for normally throwing said bolt outwardly, said bolt being provided with a longitudinal slot through which the shaft passes.
- 20 2. A lock of the kind described comprising a shaft having a groove, a spring actuated bolt, a shaft passing loosely through the bolt, means carried by the shaft for retracting the bolt upon turning of the shaft 25 in either direction, a sleeve fitting loosely upon said shaft and having a tongue fitting said groove, a knob carried by said sleeve, a disk carried by the outer end of the shaft, a circumferential groove, a second sleeve, a 30 knob carried by the second sleeve, said second sleeve being slotted at its inner end, and a pin carried by the shaft and adapted to engage said slots, said shaft being slidable with respect to both of said sleeves, and 35 with respect to the bolt and yoke, said disk having a notch adapted to register with the groove of the shaft and a knob having a tongue adapted to enter the groove of the disk.
- 40 3. A lock of the kind described comprising a bolt, a shaft passing loosely therethrough, means carried by the shaft for actuating the bolt, an inside knob carried by said shaft, the shaft being slidable with

respect to said knob, an exterior sleeve, the 45 inner end of which is adapted to be engaged and locked to the inner end of the shaft, a spring within said sleeve normally holding said shaft out of engagement with said sleeve an exterior knob upon said sleeve and 50 means carried by the outer end of the shaft for holding the same in locking engagement with said sleeve.

4. In a lock, a bolt, a shaft, a knob carried by said shaft adapted to turn therewith, an exterior sleeve, a knob carried thereby, means for forcing and holding said shaft in engagement with said sleeve, said exterior knob having a key opening registering with the sleeve, and the inner end of the 60 shaft having a slot adapted to receive the key.

5. In a lock, a bolt, a shaft upon which said bolt is loosely mounted, means carried by the shaft for retracting the bolt, a spring 65 for normally forcing the bolt outwardly, said shaft being longitudinally grooved, a sleeve having a tongue, said tongue engaging said groove, a knob on said sleeve, and having a tongue engaging the groove, a disk 70 carried by the outer end of the shaft, and having a circumferential groove of the shaft, said disk and shaft being slidable with respect to the knob and the tongue of the knob passing into the circumferential 75 groove of the disk when the same is moved inwardly, said disk being rotatable to throw the notch of the disk out of alignment with the tongue of the sleeve, a second sleeve adapted to turn loosely and also adapted to 80 engage and interlock with said shaft when the shaft is moved inwardly and a knob upon the second sleeve.

SAMUEL E. REUTTER.
